UNITED STATES PATENT OFFICE.

CASPER S. YOST, GEORGE W. BAUMHOFF, AUGUST H. HAGEMEIER, FRANK FITZLER, AND OTTO SCHMID, OF ST. LOUIS, MISSOURI, ASSIGNEES OF ONE-SIXTH TO JAMES ADKINS, OF SAME PLACE.

STREET-CAR FENDER OR GUARD.

SPECIFICATION forming part of Letters Patent No. 544,244, dated August 6, 1895.

Application filed January 5, 1895. Serial No. 533,887. (No model.)

To all whom it may concern:

Be it known that we, CASPER S. YOST, GEORGE W. BAUMHOFF, AUGUST H. HAGEMEIER, FRANK FITZLER, and OTTO SCHMID, of the city of St. Louis, in the State of Missouri, have invented a certain new and useful Improvement in Street-Car Fenders or Guards, of which the following is a full, clear, and exact description, reference being had to the accompanying drawings, forming part of this specification.

Our invention relates to an improved fender or guard for street-cars, and which is adapted to be maintained in a raised position beneath the body of the car when not in use and is adapted to be lowered down upon or close to the track, and at the same time project in a forwardly direction for use, to prevent bodies or objects getting beneath the car or being run over by the car.

Our invention consists in features of novelty hereinafter fully described, and pointed out in the claims.

Figure I is a front elevation illustrative of our invention. Fig. II is a top or plan view showing the guard and part of the car sills or timbers to which the guard is secured. Fig. III is a side elevation with part of the steps of the car broken away. Fig. IV is a detail horizontal section showing the pawl and ratchet by which the guard is held in its lower position and showing also the stop-pin for limiting the movement of the rod by which the guard is moved to its lower position. Fig. V is a detail view illustrating the movement of the crank by which the guard is moved to its lower position.

Referring to the drawings, 1 represents part of the car-body sills or timbers, 2 the platform of the car, and 3 part of the car-body.

4 represents the car-steps.

5 represents the platform or table of the guard, and which is composed of arms or bars 6, over which is stretched heavy wire-gauze or other suitable material 7. The front and ends of this platform or table are bordered by an elastic-cushioned rim 8, so that when the platform strikes a body no injurious effect upon the body will result. This rim 8

may be inflated rubber or it may be in the form of a stuffed roll.

The arm 6 is connected to the sills 1 of the car-body by means of outer links 9 and inner links 10. The links 9 are hinged or pivoted to the sills at 11, and they have a slot-and-pin connection 12 with the arm 6. The links 10 are pivoted to the inner ends of the arm 6, as shown at 13, and they are hinged to the sills 1 by means of a rock-shaft 14, secured to the under side of the sills by means of boxes 15. Secured to the shaft 14 is a lever 16, connected at its lower end to the car-body by means of a suitable spring 17.

18 represents a chain also connected to the lower end of the lever 16 at one end, and the other end of which is made fast to a crank 19, secured to the lower end of a shaft or rod 20 that is mounted against the dashboard of the platform after the manner of an ordinary brake-staff. On the upper end of the rod 20 is a handle 21, by which the rod is turned, and the movement of the rod is limited by a pin 22 (see Fig. IV) fitting in a slot 23 in one of the boxes 24, by which the rod 20 is secured to the dashboard. The rod 20 is also provided with a ratchet-wheel 25, adapted to be engaged by a pawl 26 pivoted to the floor of the platform of the car, and which engages the ratchet-wheel to hold the guard or fender in its operative position.

27 shows a spring which holds the pawl 26 to the ratchet 25.

When the guard or fender is not in use, it is held in the position shown by dotted lines, Fig. III, by means of the spring 17. In this position it is somewhat above the track, so as not to come in contact with any small object that may be lying on the track or just outside the rails of the track. In case a child or other body which the operator desires to protect or which he desires to remove from the track is approached, the operator moves the handle 21 from the position shown in full lines, Fig. V, to the position shown in dotted lines. This causes the fender to be moved from the position shown in dotted lines of Fig. III to the position shown in full lines, the spring 17 yielding to the force exerted on the rod 20, and in this position the fen-

der is held by the pawl 26. The links 9, being somewhat longer than the links 10, cause the platform 5 of the fender to move downwardly toward the track as the fender 5 is moved into operative position, and by providing the slot-and-pin connection 12 between the links 9 and the arm 6 the platform can yield upwardly in case it strikes any small object on the track after it is lowered to 10 operative position. When the fender is lowered and the platform strikes a body, the body will be caused to fall upon the platform, and thus any danger of the body getting beneath the car is prevented, and by covering the 15 platform with such material as heavy wire-netting and providing it with a cushioned border little or no injury is caused to the body by being struck by the fender. To prevent any danger of the body being thrown inwardly 20 beyond the platform when it is struck, we secure cross-strips 30 to the links 9, against which the body would strike in case it does not fall upon the wire-netting of the platform. When the danger is past, the operator releases 25 the shaft 20 by disengaging the pawl 26 from the ratchet 25, and the spring 17 draws the parts back to the position shown by dotted lines in Fig. III, the platform of the fender ascending as it recedes, so as to be maintained some distance above the track.

We claim as our invention—

1. A fender for street cars comprising the pivoted outer links, the pivoted inner links, the platform connected with the outer links 35 and hinged to the inner links, the rock-shaft, the spring connected with the rock-shaft for holding the platform in retracted position, and means, connected with the rock-shaft, for projecting the platform; substantially as described.

2. A fender for street cars comprising the pivoted outer links, the pivoted inner links, the platform having pin and slot connection with the outer links and hinged to the inner 45 links, the rock-shaft, the spring connected with the rock-shaft for holding the platform in retracted position and means connected

with the rock-shaft for projecting the platform; substantially as described.

3. In a fender for street cars, the combination of a platform, outer links connecting the platform to the car body, inner links pivoted to the platform at their lower ends, a rock-shaft to which said inner links are secured at their upper ends, a lever secured to said rock-shaft, a spring connecting the lower end of 55 said lever to the car body, an operating shaft, a chain connecting a crank on said shaft to said lever, a stop pin secured to said shaft and working in a slot in one of the boxes of 60 the shaft, and a handle on the upper end of said shaft by which the fender is moved in opposition to said spring; substantially as and for the purpose set forth.

4. A fender for street cars comprising the 65 pivoted outer links, the pivoted inner links, the platform hinged to the inner links, the rock-shaft with which the inner links are connected and by which they are pivotally supported, the lever secured to the rock-shaft, 70 the spring secured to the lever, the operating rod having a crank, the chain connecting the lever with the crank, and means for locking the rod from movement; substantially as described.

5. In a fender for street cars, the combination of a platform, outer links connecting the platform to the car body, inner links pivoted to the platform at their lower ends, a rock shaft to which said inner links are secured at 80 their upper ends, a lever secured to said rock-shaft, and a spring connecting the lower end of said lever to the car body, by means of which the platform is held in normal position, substantially as set forth.
